HARVEY L. FISHER, OF CHICAGO, ILLINOIS.

STEREOTYPER'S CASTING, SAWING, AND MATRIX-MAKING MACHINE.

Application filed November 15, 1923. Serial No. 674,912.

My invention relates to a stereotyper's casting machine and more particularly to a machine having a pair of spaced platens against one of which the matrix may be placed, being held thereagainst by suitable gauges which serve to confine the molten metal to the desired space between the platens.

Among the objects of the invention are the following:

The provision of a machine of simple, strong and durable construction, inexpensive to manufacture and which may be easily and conveniently handled;

15 The provision of a machine so arranged that the two platens may be clamped together in co-operative relationship and moved into a substantially vertical position when a casting is to be made, or moved so 20 that the bottom platen will occupy a substantially horizontal position and serve as a convenient work table while the other or top platen may also be swung, if desired, to a substantially horizontal position to form 25 an extension of the table;

The provision of means whereby the height of the bottom platen, when it is used as a work table, and also the height of the top platen if it be used as a work table, may be 30 varied to suit the convenience of the operator;

The provision of means adapted to operate automatically to lock the bottom platen when in its horizontal position;

35 The provision of means to aid in controlling the movement of the platens when clamped together from their vertical position to their co-operative horizontal position, and serving to assist in the reverse movement;

40 The provision of means to assist in moving the top platen independently of the bottom platen;

The provision of a metal pot tiltably 45 mounted on the frame of the machine in combination with means for heating the metal pot and so arranged that the molten metal may flow directly from the pot into the casting chamber when the platens are 50 in their vertical or casting position;

The provision of means whereby either or both platens may be heated preliminarily to making a casting or heated so that wet papier mâché flongs may be dried or baked to 55 form the matrices;

The provision of means of simple and in-

expensive construction for maintaining the two side gauge bars at right angles to the bottom gauge bar even though the side bars be variously spaced to make castings of different widths;

The provision of a saw for cutting off the tail of the casting or otherwise cutting up a casting, which is removably and slidably mounted on one side of one of the platens 65 in combination with suitable driving means therefor so arranged that the saw may be moved against the material while the latter remains stationary on one of the platens; and

70 The provision of a brush for beating the wet papier mâché flongs into the type, said brush preferably being supported on a jointed arm swingable over one of the platens when the latter is in its horizontal position 75 and being reciprocated by either mechanical, electrical or pneumatically operating power means.

The invention consists in the novel constructions, arrangements and devices to be 80 hereinafter described and claimed for carrying out the above-stated objects and such other objects as will appear from the following description of certain preferred embodiments illustrated in the accompanying 85 drawings in which—

Fig. 1 is a side elevational view of a machine embodying the principles of my invention, the two platens being in non-co-operative relationship and in their horizontal 90 positions;

Fig. 2 is a side elevational view of the machine, the platens being in co-operative relationship and in a vertical position;

Fig. 3 is a sectional view, on an enlarged 95 scale, taken on the line 3—3 of Fig. 2;

Fig. 4 is an elevational view of the left end of the machine when the platens are in the position shown in Fig. 1;

Fig. 5 is a detail view, on an enlarged 100 scale, of one of the spring arrangements preferably employed for assisting in moving the platens from their vertical to a horizontal position;

Fig. 6 is a sectional view, on an enlarged 105 scale, taken on the line 6—6 of Fig. 1;

Fig. 7 is an enlarged detail view showing the means preferably employed for permitting limited swinging of the two platens when in a vertical position to bring the open 110 end of the casting chamber under the mouth of the metal pot;

Fig. 8 is a plan view, on an enlarged scale, of fragmentary portions of the two platens when in the position shown in Fig. 1;

Fig. 9 is a sectional view, on a further enlarged scale, taken on the line 9—9 of Fig. 8;

Fig. 10 is a detail view of one of the stop members attached to one side of the bottom platen;

Fig. 11 is an end view of one of the double acting springs employed for assisting in swinging the top platen;

Fig. 12 is an end elevational view of the saw and its supporting frame attached to the side of the bottom platen, certain parts being broken away;

Fig. 13 is a sectional view, on an enlarged scale, taken on the line 13—13 of Fig. 12;

Fig. 14 is a vertical sectional view of one form of brush and its operating mechanism which may be employed for beating the wet papier mâché flongs into the type;

Fig. 15 is a sectional view, on an enlarged scale, taken on the line 15—15 of Fig. 14;

Fig. 16 is an elevational view, with certain portions broken away, of a modified operating mechanism for the beating brush;

Fig. 17 is a vertical sectional view of another modified form of beating brush and its operating mechanism; and

Fig. 18 is a transverse sectional view, on an enlarged scale, taken on the line 18—18 of Fig. 17.

Like characters of reference designate like parts in the several views.

Referring now to the drawings, the frame of the machine includes a pair of side members 20 which are held in spaced relation by a plurality of transverse brace rods 21, 21^a, 21^b and 21^c. Vertically extending channel members 22, placed so that their channels extend inwardly, are secured to the inner sides of the respective side members 20. Diagonally extending brace bars 23 are connected at their lower ends to the respective side members 20 and at their upper ends to plates 24 attached to the upper ends of the respective channel members 22. The side members 20 are provided with feet 25, see Fig. 3, each of which is formed with a plurality of apertures 26 adapted to receive the respective ends of the brace rods whereby the height of the side members may be varied.

The bottom platen 27 is pivotally connected at its inner end to the outer ends of a pair of L-shaped links 28, see Fig. 9, the other ends of said links being pivoted on a transversely extending rod 29, see also Fig. 8. The extremities of the rod 29 carry rollers 30 which operate in the vertically extending guideways provided in the respective channel members 22. The outer end of the bottom platen 27 rests upon the upper ends of a pair of arms 31 which are fixed at their lower ends to a tubular rock shaft

32 mounted on the transverse tie-rod 21. A metal pot 33 normally rests on the top of an upstanding support 34 carried by the frame. The metal pot is provided with a pair of arms 35, the extremities of which are pivoted to the respective plates 24 and brace bars 23. The top platen 36 is connected at its inner end to the outer ends of a pair of plates 37, see Fig. 9, the inner ends of said plates being pivoted on the rod 29. The connection of the two platens with the rod 29 is such that the top platen may be swung from a horizontal position on top of the bottom platen 27 through an arc of substantially 180° onto the metal pot 33, the metal pot serving to support the top platen when it is in the position shown in Fig. 1.

A pair of double-acting springs 38, see Fig. 8, are preferably coiled about the rod 29. One end of each spring is anchored in the adjacent link 28 and the other end thereof is anchored in the platen 36. When said springs are free of the links and platen aforesaid, the extending end portions of each spring stand preferably in the same plane as shown in Fig. 11. The springs normally hold the platen 36 in a substantially vertical position, assuming it is not secured in some other position. When the platen 36 is moved from its said vertical position down onto the bottom platen or onto the metal pot, it is against the action of the springs and the springs, therefore, check rapid descent of the platen and also assist in returning it to its said vertical position.

The platens are maintained in spaced relationship and the molten metal may be confined in the casting chamber formed therebetween by gauges of any suitable construction. In the embodiment illustrated the gauges comprise longitudinally extending bars 39 and 40, see Fig. 8, and a transversely extending bar 41 which are placed on the bottom platen over the matrix (not shown). The bottom platen adjacent one side edge is provided with a longitudinally extending groove in which a bar 42 is placed. A plurality of links 43 and 44 are pivotally connected in parallelogrammatic relation, said links being placed on the bottom platen between the bars 40 and 42. By tightening the thumb nuts 45 the links 43 and 44 may be held in the desired rigid relationship and, when the bar 40 is placed against the inner ends of the links 44, it will be exactly at a right angle to the bar 41. Stop members 46 are mounted on the other side of the bottom platen. A plurality of links 47 and 48 are pivotally connected in parallelogrammatic relationship and are placed on the platen between the stop members 46 and the gauge bar 39. When the thumb nuts 49 are tightened, the links 47 and 48 may be held in the desired rigid relationship and, when the bar 39 is placed

against the inner ends of the links 48, it will also be at a right angle to the bar 41. It will be noted from Fig. 10, that the stop members 46 are flattened on one side as at 5 46^a. The members 46 are mounted on the platen 27 so that the flattened parts 46^a will be flush with the top surface of the platen when said members are turned properly. The purpose of this arrangement will present 10

15 The gauge bars shown in the drawings are type-high. The respective L-shaped links 28 are provided with adjusting screws 50, see Fig. 9, which are adapted to bear against the under side of the bottom platen. The screws 50 are adjusted in the links so that the tops of the gauge bars will be on a line with the axis of the rod 29. The top platen is pivoted to the rod 29 in a manner 20 to bring its upper surface also on a line with the axis of the rod. The top platen, therefore, may be swung over onto the top of the gauge bars without shifting the gauge bars on the bottom platen. When 25 castings less than type-high are to be made, thinner gauge bars, of course, are used and, in that case, the screws 50 are adjusted to raise the bottom platen. The means for connecting the bottom platen to the rod 29 30 and its adjustment to accommodate gauge bars of various heights is fully described and claimed in the co-pending application of Milan H. Fisher Serial No. 597,386, filed October 27th, 1922.

35 The means for clamping the outer ends of the two platens together includes a hook member 51 mounted on each side of the top platen which is operated by a handle member 52, the hook member 51 being adapted 40 to engage a reversible catch 53 mounted on the side of the bottom platen. The clamping means mentioned is described and claimed in my co-pending application Serial No. 676,561 filed November 23, 1923.

45 When the top platen is swung over onto the bottom platen and clamped thereto, the two platens may be moved into the casting position shown in Fig. 2 by permitting the rod 29 and its rollers 30 to descend in the 50 vertically extending guideways formed in the channel members 22. I preferably provide means to prevent the platens from moving into the casting position too rapidly and also to aid the operator in moving them 55 from their casting position to their cooperative horizontal position. In the embodiment herein shown, arms 54 are fixed at one end on the rock shaft 32, the arms 54 in conjunction with the respective arms 31 60 constituting a pair of bell-cranks. The free ends of U-shaped strap members 55, see Fig. 5, are pivoted to the free ends of the respective arms 54, a stop member 56 extending through each of the members 55. 65 The medial portions of U-shaped strap

members 57 rest on top of the respective members 56. The arms of the members 57 extend downwardly against the sides of the medial portions of the respective members 55 and against the sides of the transverse 70 tie-rod 21^a, being connected, respectively, to the sides of blocks 58. Compression springs 59 are coiled about the respective co-operating members 55 and 57, being interposed between the members 56 and the 75 blocks 58. With this arrangement, when the two platens are moved from their co-operative horizontal position into their casting position, the springs 59 are compressed and rapid descent of the two platens is effectively 80 checked. The springs also aid materially in moving the two platens from the casting position into their co-operative horizontal position.

85 The means for locking the bottom platen in its horizontal position preferably includes stop members 60, see Fig. 6, operating in suitable registering slots provided in the respective channel members 22 and plates 24, said stop members, respectively, being 90 mounted on spring arms 61 fixed at their lower ends to the outer sides of the respective channel members. The under sides of the stop members are inclined or beveled at 60^a and the spring arms 61 are so formed 95 that the stop members 60 are normally positioned directly in the path of the respective rollers 30. When the platens are being moved from their casting position to their co-operative horizontal position, the rollers 100 105 30 readily move by the respective stop members 60 and the spring arms 61 instantly act to force the stop members inwardly under the respective rollers, thus locking the rod 29 against downward movement in the guideways and consequently locking the bottom platen in its horizontal position. The stop members may be readily withdrawn from the paths of the respective rollers 30 by pulling outwardly on the upper ends of the 110 spring arms 61.

A burner 62 is positioned under the metal pot 33. A burner 63 is preferably attached to the back side of the bottom platen 27. Since the burner 63 swings with said platen, 115 it is provided with a flexible tube 63^a for supplying fuel thereto.

When it is desired to make a casting, the platens are moved into the positions shown in Fig. 1. The metal in the pot 33 is heated 120 by the burner 62 and, since the platen 36 rests on top of the metal pot, it is also heated while the metal is being heated. The matrix is placed on the platen 27 and the gauge bars properly arranged thereover. If 125 desired, the bottom platen 27 may be preliminarily heated by the burner 63. When the metal in the pot 33 is brought to the proper temperature, the platen 36 is swung over onto the platen 27 and clamped thereto. 130

The spring arms 61 are pulled out to withdraw the stop members 60 from underneath the respective rollers 30 and the hingedly connected ends of the two platens descend, 5 the platens swinging into the vertical or casting position. As shown in Fig. 8, the platens are provided with a plurality of longitudinally and transversely extending ribs to stiffen them and prevent them from 10 warping. By reference to Fig. 7, it will be observed that the free ends of the arms 31 bear against the under side of the back of the bottom platen and the under side of one of the transverse ribs. The arms 31 are 15 notched at 64 for the reception of pins 65 fixed in the platen, whereby the upper ends of the two platens may be swung away from or toward the metal pot to bring the casting chamber directly under the mouth of the 20 metal pot when tilted. The molten metal, therefore, may flow directly from the metal pot into the casting chamber. After the casting has been made, the platens are swung from the vertical or casting position back 25 to their co-operative horizontal position. The upper platen is unclamped and, under the influence of the springs 38, it may be readily moved to a position out of the way. The machine is of very simple construction 30 and requires very little machine work. Its parts are few in number and they may readily be assembled. The springs 59 materially aid in the handling and the control of the two platens when they are clamped 35 together and are being moved from one position to the other, while the springs 38 materially aid in moving the platen 36 from either of its two horizontal positions toward the intermediate vertical position. 40 The saw used in cutting off the tail of the casting is preferably mounted on the side of the platen 27, in which case a smooth working surface may be readily obtained on top of the platen by removing therefrom the gauge bars, the parallelogrammatically arranged links and the bar 42, and by turning the stop members 46 so that their flattened surfaces 46^a are even with the top of the platen. 45 A rail 66, see Figs. 12 and 13, is fastened to one side of the platen 27 by bolts 67. The frame of the saw includes a member 68 which is slidably mounted on the rail 66 by a plurality of L-shaped retaining members 69. The member 68 carries a hub member 70 in which a sleeve 71 is journaled. A bolt 72 extends through the sleeve 71, the saw 73 being secured on the inner end of the sleeve by a nut 74 on the inner end of the bolt. 55 A beveled gear 75 is mounted on the outer end of the bolt 72; the sleeve 71, bolt 72 and gear 75 being held against relative axial movement by a nut 76 threaded on the outer end of the bolt 72. The saw frame may be moved backwardly and for-

wardly on the rail 66 by a handle 77, the upper end of which is secured to the rear end of the member 68 and the lower end of which is secured to a plate 78 attached to the member 68, the plate 78 serving to prevent the hand of the operator from coming into contact with the saw. The driving means for the saw preferably includes a shaft 79, see Figs. 1 and 2, journaled in suitable bearings provided on the frame of 75 the machine and carrying a beveled gear 80. The lower end of the shaft 81 is journaled in a head 82 which is rockable on the shaft 79, said shaft 81 having a beveled gear 83 in mesh with the gear 80. The upper end of 80 the shaft 81 extends into the lower end of a tubular shaft 84, the upper end of the latter being journaled in a head 85 formed integrally with the hub member 70, the shaft 84 being provided with a gear 86 in mesh with the gear 75. The shafts 81 and 84 have a splined connection, one having a longitudinally extending slot while the other has a rib or a pin adapted to fit into the slot. The shaft 79 may be driven by any suitable 90 means, for example, it may be provided with a pulley 87 connected by a belt 88 operating over a pulley 89 driven by a motor 90.

It will be obvious that the saw frame may be pushed so as to maintain the saw in cutting engagement with the casting. The connection between the shafts 81 and 84 is such that the saw frame may be readily removed from the rail 66 when the platens are in the position shown in Fig. 2. By this arrangement the saw may be swung into the position shown in dotted lines in Fig. 2 when a casting is to be made and thus be away from and not affected by the heat. 100

The brush for beating the wet papier mâché flings into the type and its operating mechanism are mounted on the end of an arm 91 hinged to the outer end of an arm 92, the inner end of the arm 92 being journaled on a vertically extending post 93 110 attached to one side of the frame of the machine. The operating mechanism may be of any of the forms shown in Figs. 14 to 18, inclusive. 115

In the construction shown in Figs. 14 and 15, the beating brush 94 is mounted on the lower end of a rod 95 reciprocably mounted in a casing 96. The upper end of the rod 95 extends into a casing 97 which is made in the form of a handle. A stop member 98 is fixed to the rod and a spring 99 coiled about the rod 95 is interposed between the upper side of the stop member 98 and the under side of the top of the casing 97. The rod 95 and the beating brush 94 carried thereby are normally urged by the spring 99 into their lowermost positions. A shaft 100 is journaled in the casing 96 and carries a gear 101 in mesh with a pinion 102 mounted on the armature shaft of a motor 103, 130

A cam member 104 is fixed to one side of the gear 101 and bears against a roller 105 mounted on the side of the rod 95. The motor drives the gear 101 so that it rotates 5 in the direction indicated by the arrow, Fig. 15. When the part 104^a of the cam passes from underneath the roller 105, the rod 95 descends and the bristles of the brush 94 impart a quick blow to the flong placed on top 10 of the type. The jointed arms 91 and 92 permit the beating brush to be moved to any desired position over the flong. The arrangement is such that the lower ends of the bristles of the beating brush, when the brush 15 descends, do not quite touch the bottoms of the various recesses in the type; consequently, the bristles of the brush while effectively beating the flong into the type, do not break or weaken the flong in doing so. 20 In the construction shown in Fig. 16, the cam member 104 is connected directly on the end of a shaft 106, the latter being connected to a flexible shaft 107, which is attached to any suitable power means, for example, the motor 90. With this arrangement one motor may be made to serve as a power means for driving the saw and also for driving the beating brush. 25

In the construction shown in Fig. 17, the beating brush is operated by pneumatic means. The brush is mounted on the lower end of a stem carried by a piston 108 which operates in a cylinder 109. Air under pressure is admitted to the cylinder through a 30 pipe 110 and an opening 111 in the cylinder wall. The piston 108 is provided with an external circumferential groove 112 and a vertical passageway 113. A plurality of radial passageways 114 lead from the groove 35 112 to the passageway 113. The piston is provided with an annular shoulder 115 and the cylinder is provided with a similar shoulder 116. A compression spring 117 is coiled about the piston 108, being interposed between the shoulders 115 and 116. The cylinder walls are provided with outlet openings 118. The spring 117 normally maintains the piston 108 in its uppermost position. When air is admitted to the cylinder through the 40 opening 111, it passes into the groove 112, through the radial passageways 114, and the vertical passageway 113 and a pressure is built up on top of the piston which forces the piston downwardly into its dotted line 45 position, thus causing the brush to descend and beat the flong into the type. When the piston is in its dotted line position, the air escapes from the cylinder through the passageway 113, radial passageways 114, groove 50 112, and the outlet openings 118, whereupon, the spring 117 returns the piston to its initial position. 55

It will be obvious from the foregoing description that a machine embodying the 60 principles of my invention may be used for four primary purposes: First, for beating the wet papier mâché flongs into the type; second, for baking or drying the flongs, in which case the burner 63 may be utilized to heat the bottom platen and the top platen 70 75 may be heated by the burner under the metal pot, the two heated platens being then clamped together with the wet flong on the type in between, thereby drying the flong from both sides simultaneously; third, for 80 making castings from the matrices; and fourth, for sawing the castings after they have been made. The construction is such that the saw may readily be removed from the rail 66 while matrices or castings are 85 being made, and the beating brush may be swung to one side out of the way when castings are being made or sawed. When the matrices are to be made or a casting is to be sawed, the bottom platen serves as a convenient work table upon which to perform the work while the top platen may be used as an extension of the table upon which the gauge bars, etc. may be placed. By adjusting the feet 25 relative to the frame the table 90 may be positioned at the height most convenient to the operator. The platens, when in the position shown in Fig. 1, may be used as a convenient work table for many purposes. Furthermore, the construction of 95 the machine is such that it may be sold as a casting machine without the saw and beating brush arrangements, thus lessening the initial investment of the purchaser. The purchaser may subsequently add either the 100 saw or beating brush arrangements, or both, whenever desired. 105

I do not intend to limit my invention to the details of construction shown and described except only in so far as certain of the appended claims are specifically so limited, as it will be obvious that various modifications may be made without departing from the principles of my invention. 110

I claim:

1. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal position, and a second platen pivotally mounted on said first named platen and movable therewith on said frame. 115
2. In a machine of the class described, the combination of a frame, two platens pivotally connected together at their adjacent ends, and means on said frame for holding said platens either in horizontal position 120 aligned with each other or folded together in vertical position. 125
3. In a machine of the class described, the 130

- combination of a frame, two platens pivotally connected together at their adjacent ends, and means on said frame for holding said platens in horizontal position in alignment with each other or in either horizontal position or vertical position folded together.
4. In a machine of the class described, the combination of a frame, a platen movable on the frame from horizontal position to vertical position thereon, a second platen pivotally connected with the said first named platen and adapted to fold over upon said first named platen, and vertically disposed guide means on said frame for controlling the movement of the platens from horizontal position to vertical position on said frame.
5. In a machine of the class described, the combination of a frame, a horizontal rock shaft revolvably mounted in said frame, a platen connected with said rock shaft and movable thereabout from horizontal position to vertical position on said frame, a second platen pivotally connected with said first named platen and adapted to fold over upon said first named platen, and vertically disposed guide means on said frame engaging the platens near their connected ends for guiding the movement of the platens from horizontal position to vertical position.
6. In a machine of the class described, the combination of a supporting frame including guide means at each side thereof, a transverse member having its ends slidably connected to said respective guide means, a platen hingedly connected at one end to said member, means for supporting the other end of said platen, said guide means and supporting means being so arranged that said platen may be moved either into a vertical or a horizontal position, a second platen hingedly connected at one end to said member, and means to clamp the other end of said second platen to said first platen.
7. In a machine of the class described, the combination of a supporting frame including inwardly disposed guideways at each side thereof, a transverse member, rollers on said member and operating in said respective guideways, a platen hingedly connected at one end to said member, means for supporting the other end of said platen, said guideways and supporting means being so arranged that said platen may be moved either into a vertical or a horizontal position, a second platen hingedly connected at one end to said member, and means to clamp the other end of said second platen to said first platen.
8. In a machine of the class described, the combination of a supporting frame including guide means at each side thereof, a platen pivotally and slidably connected at one end to said guide means, means for supporting the other end of said platen, said guide means and said supporting means be-
- ing so arranged that said platen may be moved either into a vertical or a horizontal position, a second platen hingedly connected at one end to the pivoted end of the first platen, means to clamp the other end of said second platen to said first platen, said second platen being swingable from a horizontal position atop the first platen into another horizontal position, and means to support the second platen in its other horizontal position.
9. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal position, a second platen, means connecting said second platen to the first platen, and means to lock said first platen in its horizontal position.
10. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal position, a second platen, means connecting said second named platen to the first platen, and means on said frame which operates automatically to lock said first platen in its horizontal position.
11. In a machine of the class described, the combination of a supporting frame including guide means at each side thereof, a transverse member having its ends slidably connected to said respective guide means, a platen hingedly connected at one end to said member, means for supporting the other end of said platen, said guide means and supporting means being so arranged that said platen may be moved either into a vertical or a horizontal position, a second platen hingedly connected at one end to said member, means to clamp the other end of said second-named platen to said first-named platen, and means on said frame which operates automatically to lock said member against downward movement relative to said frame, for the purpose specified.
12. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal posi-

- tion, a second platen hingedly connected at one end to the pivoted end of the first platen, means to clamp the other end of said second platen to said first platen, said second platen being swingable from a horizontal position atop the first platen into another horizontal position, and means normally tending to hold said second platen in a substantially vertical position when the first platen is in its horizontal position. 10
13. In a machine of the class described, the combination of a supporting frame including guide means at each side thereof, a transverse member having its ends slidably connected to said respective guide means, a platen hingedly connected at one end to said member, means for supporting the other end of said platen, said guide means and supporting means being so arranged that said platen may be swung either into a vertical or a horizontal position, a second platen hingedly connected at one end to said member, means to clamp the other end of said second platen to said first platen, and a 20 spring coiled about said member and having its ends connected to said respective platens, for the purpose specified. 25
14. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal position, a second platen, means connecting said second platen to said first platen, and means to vary the height of said frame, for the 30 purpose specified. 35
15. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal position, a second platen hingedly connected at one end to the pivoted end of the first platen, means to clamp the other end of said second platen to said first platen, said second platen being swingable from a horizontal position atop the first platen into another horizontal position, means to support the second platen in its other horizontal position, and means to vary the height of said frame, for the 40 purpose specified. 50
16. In a machine of the class described, the combination of a supporting frame including guide means at each side thereof, a platen pivotally and slidably connected at one end to said guide means, means for supporting the other end of said platen, said 55
- guide means and supporting means being so arranged that said platen may be moved either into a vertical or a horizontal position, a second platen, means connecting said second platen to said first platen, and means to assist movement of the platens from a vertical to a horizontal position and to assist in the control of the movement of the platens in the reverse direction. 70
17. In a machine of the class described, the combination of a supporting frame including guide means at each side thereof, a platen pivotally and slidably connected at one end to said guide means, means for supporting the other end of said platen, said 75 guide means and supporting means being so arranged that said platen may be moved either into a vertical or a horizontal position, a second platen, means connecting said second platen to said first platen, and spring means to assist movement of the platens from a vertical to a horizontal position and to assist in the control of the movement of the platens in the reverse direction. 80
18. In a machine of the class described, the combination of a supporting frame including guide means at each side thereof and a relatively stationary part, a platen pivotally connected intermediate its ends to said frame, one arm of said bell-crank means supporting the other end of said platen, said 85 guide means and bell-crank means being so arranged that said platen may be moved either into a vertical or a horizontal position, a second platen, means connecting said second platen to said first platen, and spring means between said stationary part and the other arm of said bell-crank means, for the 90 purpose specified. 95
19. In a machine of the class described, the combination of a supporting frame including guide means at each side thereof and a relatively stationary part, a platen pivotally and slidably connected at one end to said guide means, a rock shaft journaled on said frame, an arm fixed to said shaft for supporting the other end of said platen, said 100 guide means and arm being so arranged that said platen may be moved either into a vertical or a horizontal position, a second platen, means connecting said second platen to said first platen, a second arm fixed to said shaft, and spring means between said 105 stationary part and said second arm, for the purpose specified. 110
20. In a machine of the class described, the combination of a supporting frame including guide means at each side thereof and a relatively stationary part, a platen pivotally and slidably connected at one end to said guide means, a rock shaft journaled on said frame, an arm fixed to said shaft 115 for supporting the other end of said platen, 120
- 130

said guide means and said arm being so arranged that said platen may be moved either into a vertical or a horizontal position, a second platen, means connecting said second platen to said first platen, a second arm fixed to said shaft, a link pivoted to said second arm and having a stop member, and a spring coiled about said link between said stop member and said stationary part, for 10 the purpose specified.

21. In a machine of the class described, the combination of a supporting frame including guide means at each side thereof, a platen pivotally and slidably connected at one end 15 to said guide means, means for supporting the other end of said platen, said guide means and supporting means being so arranged that said platen may be moved either into a vertical or a horizontal position, a second platen, means connecting said second platen to said first platen, and a metal pot 20 tiltably mounted on said frame and so arranged that molten metal may flow therefrom into the casting chamber when said 25 platens are in the vertical position.

22. In a machine of the class described, the combination of a supporting frame including guide means at each side thereof, a platen pivotally and slidably connected at 30 one end to said guide means, means for supporting the other end of said platen, said guide means and supporting means being so arranged that said platen may be moved either into a vertical or a horizontal position, a second platen, means connecting said 35 second platen to said first platen, a metal pot tiltably mounted on said frame and so arranged that molten metal may flow therefrom into the casting chamber when said 40 platens are in the vertical position, and means for heating said pot.

23. In a machine of the class described, the combination of a supporting frame including guide means at each side thereof, a platen pivotally and slidably connected at 45 one end to said guide means, means for supporting the other end of said platen, said guide means and supporting means being so arranged that said platen may be moved either into a vertical or a horizontal position, a second platen, means connecting said 50 second platen to said first platen, a metal pot tiltably mounted on said frame and so arranged that molten metal may flow therefrom into the casting chamber when said 55 platens are in the vertical position, means for heating said pot, and independent means for heating one of said platens, for the purpose specified.

60 24. In a machine of the class described, the combination of a supporting frame including guide means at each side thereof, a platen pivotally and slidably connected at one end to said guide means, means for supporting the other end of said platen, said

guide means and supporting means being so arranged that said platen may be moved either into a vertical or a horizontal position, a second platen, means connecting said second platen to said first platen, a metal pot 70 tiltably mounted on said frame and so arranged that molten metal may flow therefrom into the casting chamber when said platens are in the vertical position, a burner for heating said pot, and an independent 75 burner for heating one of said platens, for the purpose specified.

25. In a machine of the class described, the combination of a supporting frame including guide means at each side thereof, a platen pivotally and slidably connected at one end to said guide means, means for supporting the other end of said platen, said guide means and supporting means being so arranged that said platen may be moved 80 either into a vertical or a horizontal position, a second platen hingedly connected at one end to the pivoted end of the first platen, means to clamp the other end of said second platen to said first platen, said second 85 platen being swingable from a horizontal position atop the first platen into another horizontal position, a metal pot tiltably mounted on said frame under the second platen when it is in its other horizontal 90 position and so arranged that molten metal may flow therefrom into the casting chamber when the platens are in the vertical position, means for heating said pot, and means for heating the first platen. 100

26. In a machine of the class described, the combination of a supporting frame including guide means at each side thereof, a platen pivotally and slidably connected at one end to said guide means, means for supporting the other end of said platen, said guide means and supporting means being so arranged that said platen may be moved either into a vertical or a horizontal position, a second platen, means connecting said 110 second platen to the first platen, and means whereby said platens may be rocked a limited extent when in their vertical position, for the purpose specified.

27. In a machine of the class described, the combination of a frame, two platens pivotally connected together at their adjacent ends, means on said frame for holding said platens either aligned with each other in horizontal position or folded together in vertical position, and a metal pot movably mounted on said frame and so arranged that molten metal may flow therefrom into the casting chamber when said platens are in the vertical position. 115 120 125

28. In a machine of the class described, the combination of a frame, two platens pivotally connected together at their adjacent ends, a metal pot tiltably mounted on said frame near the upper end thereof, and 130

means carried by the frame for holding said platens either aligned with each other in horizontal position at the upper end of the frame above said metal pot or folded together in substantially a vertical position

5 together in substantially a vertical position and adjustable slightly toward and from the metal pot in such position that molten metal is adapted to flow from the pot into the casting chamber when said platens are held in

10 vertical position.

29. In a machine of the class described including a pair of spaced platens, of means to confine the molten metal in the space therebetween comprising a bottom member,

15 a pair of side members, side stop means carried by one of said platens, and a plurality

of links arranged in parallelogrammatic relation and interposed between said stop means and one of said side members, for the purpose specified. 20

30. In a machine of the class described, including a pair of spaced platens, of means to confine the molten metal in the space therebetween comprising a bottom member,

25 a pair of side members, side stop means carried by one of said platens, a plurality of links arranged in parallelogrammatic relation and interposed between said stop means and one of said side members, and means to fix said links in the position desired, for the purpose specified. 30
